(57) **CLAIM**

The ornamental design for a spiral wound battery, as shown and described.

DESCRIPTION

FIG. 1 is a front perspective view of an embodiment of a battery in accordance with the present invention. The battery includes terminals on the top, a handle attached to a center of the top and hinged such that it rests in a recessed portion of the front half of the top, two vertical separators in each of the front and the back, a horizontally ribbed portion on each side, and a rounded, protruding edge portion along the junction between the top of the battery and the main body of the battery. The sides of the battery are recessed inwardly in correspondence with the horizontal ribs.

FIG. 2 is a front view of a battery in accordance with the FIG. 1 embodiment.

FIG. 3 is a top view of a battery in accordance with the FIG. 1 embodiment; and,

FIG. 4 is a side view of a battery in accordance with the FIG. 1 embodiment.
